US00D959891S

(12) **United States Design Patent** (10) Patent No.: **US D959,891 S**
(45) Date of Patent: ** Aug. 9, 2022

(54) **COOKWARE**

(71) Applicant: **Lagom Kitchen Co.**, Culver City, CA (US)

(72) Inventors: **Amir Tehrani**, Los Angeles, CA (US); **Zachary Rosner**, Los Angeles, CA (US); **Stuart Harvey Lee**, Forest Hills, NY (US); **Jochen Schaepers**, New York, NY (US)

(73) Assignee: **Lagom Kitchen Co.**, Culver City, CA (US)

(**) Term: **15 Years**

(21) Appl. No.: **29/800,673**

(22) Filed: **Jul. 22, 2021**

(57) **CLAIM**

The ornamental design for a cookware, as shown and described.

DESCRIPTION

FIG. 1 is a top perspective view of a cookware showing our new design;

FIG. 2 is a bottom perspective view thereof;

FIG. 3 is a right side elevation view thereof, the left side elevation view being a mirror image thereof;

FIG. 4 is a front elevation view thereof;

FIG. 5 is a rear elevation view thereof;

FIG. 6 is a top plan view thereof; and,

FIG. 7 is a bottom plan view thereof.

The broken lines showing portions of the cookware form no part of the claimed design.

1 Claim, 3 Drawing Sheets
